PATTERN FOR FAGOTED YOKES

Mildred Augustin, Philadelphia, Pa.

Application September 9, 1950, Serial No. 184,020

9 Claims. (Cl. 33—12)

1

The present invention relates to patterns and guides for making the yoke-portion of a blouse or dress.

The object of the present invention is to provide a guide or pattern for making fagoted stitching.

Referring now to the drawings, wherein like reference characters indicate like parts:

Figure 1 represents a perspective view of a fagoted yoke of the present invention as applied to a woman's blouse.

Figure 2 represents a fragmentary plan view of a portion of the blouse of Figure 1.

Figure 3 represents a plan view of the yoke-making pattern of the present invention with two rows of bias tape basted thereto and with a partial row of fagoted stitches applied between said bias tapes.

Figure 4 represents a cross-sectional view taken generally along line 4—4 of Figure 3.

Figure 5 represents a fragmentary cross-sectional view, on an enlarged scale of a single row of bias tape basted to the pattern of Figure 3.

Figure 6 represents a fragmentary plan view of the yoke-making pattern and bias tape basted thereto showing the first step in the formation of the fagoted stitch of the present invention.

Figure 7 represents a plan view similar to the plan view of Figure 6 showing the second step in the formation of the fagoted stitch of the present invention.

Figure 8 represents a plan view similar to the plan view of Figures 6 and 7 showing the next step in the formation of the fagoted stitch of the present invention.

Figure 9 represents a plan view, similar to that of Figures 6, 7 and 8, showing two completed stitches and the start of a third fagoted stitch of the present invention.

Figure 10 represents an enlarged fragmentary plan view of two rows of bias tape with a row of fagoted stitching of the present invention intervening said rows of bias tape.

Referring particularly to Figure 3, there is illustrated a pattern 15, which may be formed of paper and which is generally oval shaped with an opening 16 at the center thereof and with a wedge-shaped portion removed from one end thereof to provide an incomplete ellipse. The pattern 15 has a plurality of generally concentric lines 17 printed thereon to provide spaced guides 18 along which strips of bias tape 19 may be temporarily secured (as by the basting stitches 20).

The pattern 15 is shaped so that when the edges 21 and 22 thereof are placed in abutting relationship the pattern 15 will form a generally frusto-

2

conical shield or cover or pattern which conforms generally to the outline or shape of the neck-portion or yoke-portion of a woman's blouse or dress or the like.

Therefore, a yoke or shoulder-portion for a garment made according to the pattern 15, when completed and affixed to a blouse or dress, will fit neatly and properly upon the shoulders of the wearer of the garment. It is to be understood that the pattern 15 may be prepared in a variety of sizes and shapes so that blouses or dresses embodying the yoke of the present invention may be made in a variety of sizes according to the demands of the person ultimately wearing the garment. It is also to be understood that the pattern may be made of fabric or any other suitable material.

Between the concentric rows of elliptical guides 18 there are imprinted upon the pattern 15 generally diagonal spaced guide-lines 23 for a purpose to be hereinafter explained.

The fagoted stitch of the present invention shown in detail in Figures 2 and 6 to 10, inclusive, is formed as follows:

With the rows of bias tape 19 temporarily secured to the pattern 15 by the basting-stitches 20, a strand or yarn 24 from which the fagoted stitches are to be formed is knotted at one end (as at 25) and passed through one of the bias tapes 19-a but not through the pattern 15 therebeneath. Thereafter, the yarn 24 is extended diagonally across the pattern 15 to the next adjacent row of bias tape 19-b, along the diagonal line 23-a which extends from the tape 19-a to the tape 19-b.

Then the yarn 24 is passed through the tape 19-b (closely adjacent the edge 26) but not through the pattern, as is shown particularly in Figure 6.

Thereafter the yarn 24 is passed completely around the strand 27 which extends between the tapes 19-a and 19-b. The free end of the yarn may pass from the right or forward side of the strand 27 to the left or rearward side thereof (as illustrated in Figure 7). The forward side of the strand 27 is that side which generally represents the direction of advance of the strand 27 parallel to the tapes 19-a and 19-b, and is that side of the strand which makes an obtuse angle with the adjacent edge of the fabric.

After the free end of the yarn 24 has been passed completely around the strand 27, it is extended diagonally toward the tape 19-a (along the guide-line 23) where it is secured to the tape

19-a (along the edge 29 thereof). This step is shown particularly in Figure 8.

A second fagoted stitch (according to the present invention) is made when the free end of the yarn 24 is passed completely around the strand 30, which now extends from the tape 19-b to the tape 19-a and is thereafter extended toward the tape 19-b along the guide-line 31. Thereafter succeeding stitches are made in the manner shown in Figures 6 to 8, inclusive, using the 10 guide-lines 23 to indicate where the yarn 24 should be connected to the tapes 19.

Succeeding stitches are completed, as above described, to form one row of fagoted stitching, shown partially completed in Figure 3, and shown 15 in an enlarged fragmentary view in Figure 10, until the row of stitches is complete between the edges 21 and 22 of the pattern 15. Thereafter the next adjacent (as well as the succeeding rows) of fagoted stitches may be made according to the 20 method hereinabove described.

When completed, alternate rows of bias tape and fagoted stitching will be secured to the pattern 15 to form the yoke shown in Figures 1 and 2.

When all the rows of fagoted stitches are complete and a finishing strip of bias tape (not shown) interconnects the ends of the tapes 19 along each of the edges 21 and 22 of the pattern 15, the basting stitches 26 may be removed and the completed yoke 32 will be separated from the pattern 15. Thus, the pattern 15 may be used again to make additional yokes and will not be destroyed after one yoke is completed.

The outermost row 19-a of the bias tape may then be secured to the upper portion 33 of the blouse 34 and buttons, snaps or other fasteners may be secured to the finishing strips of bias tape (not shown) along the edges 21 and 22.

The fagoted stitching is particularly attractive and desirable because it does not form straight or diagonal strands of yarn between the rows of bias tape but, when completed according to the method hereinabove described, produces interconnecting strands of yarn which have generally radially-extending portions 35 with the shorter interconnecting diagonal portions 36 therebetween. This is shown particularly in Figures 2 and 10.

The yoke made of fagoted stitches according to the present invention is desirable because the pattern 15, which is used as a guide during the formation of the stitches and the formation of the yoke, may be used repeatedly and will not be destroyed after one yoke is completed.

It is to be understood that fagoted sttches may be embodied in garments or used in other items (such as table cloths, doilies, etc.) and is not intended to be limited solely to use in the formation of yokes or collars for blouses or dresses or the like. Thus, it may be used as decorative stitching intervening any two parallel, spaced rows of fabric.

The yoke is particularly desirable because it fits smoothly and neatly about the shoulders, when made according to the pattern of the present invention. Moreover, it can be applied either as a decorative component of blouses for girls or women, or may be used (when made according to a smaller pattern) as the entire shoulder or bodice-portion of a dress for small girls or children.

The present invention may be embodied in other specific forms without departing from the spirit or essential attributes thereof, and it is therefore desired that the present embodiment

be considered in all respects as illustrative and not restrictive, reference being had to the appended claims rather than to the foregoing description to indicate the scope of the invention.

Having described my invention, what I claim as new and desire to protect by Letters Patent is the following:

1. A pattern for making fagoted yokes, said pattern being generally oval-shaped and having a central aperture and a pair of spaced edges to provide a truncated cone when said edges are in abutting relationship, said pattern having imprinted thereon a plurality of generally concentric, oval, spaced lines with diagonal guide-lines extending between said concentric guide-lines, said diagonal lines forming a plurality of generally isosceles-shaped areas between said concentric guide-lines.

2. A pattern for use in making fagoted material, said pattern comprising a thin sheet which is generally oval-shaped and has a central aperture and a pair of spaced edges to provide a truncated cone when said edges are in abutting relationship, a plurality of generally parallel lines on said sheet and a plurality of relatively short lines on said sheet intervening the said generally parallel lines and extending at an acute angle thereto.

3. A pattern for use in making fagoted material, said pattern comprising a thin sheet of flexible material which is generally oval-shaped and has a central aperture and a pair of spaced edges to provide a truncated cone when said edges are in abutting relationship, a plurality of generally parallel lines on said sheet and a plurality of relatively short lines on said sheet intervening the said generally parallel lines and extending at an acute angle thereto.

4. A pattern for use in making fagoted material, said pattern comprising a thin sheet of flexible perforable material which is generally oval-shaped and has a central aperture and a pair of spaced edges to provide a truncated cone when said edges are in abutting relationship, a plurality of generally parallel lines on said sheet and a plurality of relatively short lines on said sheet intervening the said generally parallel lines and extending at an acute angle thereto.

5. A pattern for use in making fagoted material, said pattern comprising a thin sheet which is generally oval-shaped and has a central aperture and a pair of spaced edges to provide a truncated cone when said edges are in abutting relationship, a plurality of generally parallel lines on said sheet and a plurality of relatively short lines on said sheet intervening the said generally parallel lines, said relatively short lines in combination with the generally parallel lines defining a plurality of adjacent triangular areas.

6. A pattern for use in making fagoted material, said pattern comprising a thin sheet which is generally oval-shaped and has a central aperture and a pair of spaced edges to provide a truncated cone when said edges are in abutting relationship, a plurality of generally parallel lines on said sheet and a plurality of relatively short lines on said sheet intervening the said generally parallel lines, said relatively short lines in combination with the generally parallel lines defining a plurality of adjacent triangular areas between alternate pairs of adjacent generally parallel lines.

7. A pattern for use in making fagoted material, said pattern comprising a thin sheet which is generally oval-shaped and has a central aper-

ture and a pair of spaced edges to provide a truncated cone when said edges are in abutting relationship, a plurality of generally parallel lines on said sheet and a plurality of relatively short lines on said sheet intervening the said generally parallel lines and disposed at an acute angle to the generally parallel lines.

8. A pattern for use in making fagoted material, said pattern comprising a thin sheet which is generally oval-shaped and has a central aperture and a pair of spaced edges to provide a truncated cone when said edges are in abutting relationship, a plurality of generally parallel lines on said sheet and a plurality of indicator-markings on said sheet at regularly-spaced intervals along each of said generally parallel lines and extending at an acute angle thereto.

9. A pattern for use in making fagoted material, said pattern comprising a thin sheet which is generally oval-shaped and has a central aperture and a pair of spaced edges to provide a truncated cone when said edges are in abutting

10

15

20

relationship, a plurality of generally parallel lines on said sheet and a plurality of indicator-markings on said sheet at regularly-spaced intervals along each of said generally parallel lines and extending at an acute angle thereto, said indicator-markings on each line being offset with respect to adjacent markings on adjacent lines.
